CLAIM

The ornamental design for an eyeglass holder, as shown and described.

DESCRIPTION

FIG. 1 is a front elevational view of an eyeglass holder showing my new design;

FIG. 2 is a top view thereof;

FIG. 3 is a right side elevational view thereof, the left side being a mirror image;

FIG. 4 is a bottom plan view thereof;

FIG. 5 is a cross sectional view taken along line 5—5 of FIG. 1, the rear fastening button being removed; and,

FIG. 6 is a rear view thereof with the affixing button in place.
